BUTTER PACKAGE AND METHOD OF
MAKING SAME

Albert Lowenfels, White Plains, N. Y.

Application November 17, 1933, Serial No. 698,480

4 Claims. (Cl. 206—46)

My invention relates to packaging butter, and includes both the form and arrangement of the blocks or "bricks" of butter, and also the means and method by which such arrangement is made possible and by which it is made permanent throughout the process of handling, from producer, through dealer to consumer.

I accomplish the objects of the invention in the manner illustrated in the accompanying drawing, in which

Figure 1 is a perspective of a single block or "brick" of butter;

Figure 2 is a perspective view showing the arrangement of the blocks in the open carton, with a base row consisting of three blocks arranged alternately so that the base of the middle block faces upwardly and forms a base for supporting a single block above—the assembly presenting, at the end, the appearance of a triangle of the same shape as the individual blocks;

Figure 3 is a perspective view of the package as it appears when the carton is closed.

Similar numerals refer to similar parts throughout the several views.

Referring to the drawing, a single brick or block of butter is in the form of a triangular prism as illustrated in Figure 1. It has two end surfaces 5, and three side faces or facets 6, 7, and 8. In cross-section, these blocks are equilateral triangles. The particular facet on which the block rests at any moment may be regarded as the base. The length of the prism varies but ordinarily is approximately two and one-half times the width of one of the facets.

It will be noted that when the butter is being marketed, each block will be separately wrapped, for example, in oiled or waxed tissue paper, or other appropriate wrapping.

In packaging the butter, the blocks are arranged as illustrated in Figure 2, with three blocks arranged side by side in the base row. They are placed alternately, so that the middle block stands upon its apex, and one of the facets lies horizontally on a plane with the apices of the adjacent blocks. The fourth block is placed upon the middle block of the base row, with its base facet resting upon the up-turned facet of the middle block. The result is that the assembly produces an equilateral triangle of the same general shape as the individual blocks.

The blocks are held in this relation by means of a carton which has a central section 10, and two side sections 12, 13. The central section is of the size and shape of the base of the composite triangular prism just described. The side

sections 12, 13, which are hinged to it, are of the size and shape of the sides of said composite prism, thus reaching to the apex thereof when the carton is closed. The side section 13 has a pasting strip for pasting against the upper edge of the opposite side section 12, when the carton is closed. The central section 10 has two end flaps 16, for covering the ends of the assembled prism. The section 13 has two end flaps 18 for overlapping the flaps 16 when the carton is closed, and the section 12 has end flaps 20 for overlapping the sections 18 when the carton is closed. The flaps 20 have tongues 22 for entering slots 24 formed in the flaps 18 for holding the carton closed. Thus, the closed carton with its contents, presents the form of a triangular prism, which, in the present instance, is an equilateral triangular prism, resulting from the fact that the individual blocks themselves are equilateral. It is not essential, however, that the triangular ends be equilateral, as they may be in the form of isosceles triangles, in which event the carton itself will have a corresponding form.

It will be observed that a carton constructed in accordance with my invention has but three main foldable sections instead of the more usual number of four. The blocks of butter when sliced at right angles to the length of the prism, produce butter "patties" of triangular outline. Consequently, they give the appearance of being larger than four-sided "patties" having the same weight and thickness. That is to say, a "patty" of a given bulk and thickness will appear larger when having only three sides than if the outline were rectangular. It will also be observed that the complete package has four prismatic blocks, which is the usual number packed in a single carton in accordance with current practice, and yet with my construction and arrangement the carton requires but three main sections.

I claim:

1. A butter package including a plurality of identical blocks of butter, each in the form of an equilateral triangular prism, the blocks being arranged with at least one facet of each contiguous to and co-extensive with a facet of another block.

2. A butter package consisting of four identical blocks of butter, each in the shape of a triangular prism, the blocks being arranged with a base row of three blocks alternately placed so the base of the center block will face upward, the fourth block being centrally placed

on the center block of the base row, to thereby form an assembly which in itself constitutes a triangular prism and in which said center block is completely encircled by said other blocks, and means for holding the blocks in the relative positions described.

3. A butter package comprising four identical blocks of butter, each in the shape of an equilateral triangular prism, the package having three of the blocks arranged in a base row in alternate relation, whereby one of the facets of the center block faces vertically upward, the fourth block forming the apex portion of a composite prism of the same shape as, but greater size than the individual blocks, and a carton for holding the blocks in this relation.

4. A butter package comprising a triangular composite prism composed of four equilateral

triangular butter prisms of equal size and shape, and a carton for inclosing said composite prism, said carton having a central base section for supporting the composite prism of an area corresponding to the area of two facets of the individual prisms, arranged side by side, the carton having two side sections joined to the central section and fitting the sides of the composite prism, a pasting strip along one edge of one of said sections for holding the carton closed circumferentially, two adjacent sections of the carton having end flaps to cover the ends of the composite prism, one of the end flaps having a tongue and the other a slit for the reception of said tongue for holding the end flaps closed. 10 15
